UNITED STATES PATENT OFFICE

90,631

DESIGN FOR A SHOE

Chester F. Reith, Clayton, Mo., assignor to The Juvenile Shoe Corporation of America, Aurora, Mo., a corporation of Missouri

Application June 10, 1933. Serial No. 48,368

Term of patent 3½ years

To all whom it may concern:

Be it known that I, CHESTER F. REITH, a citizen of the United States of America, residing at Clayton, county of St. Louis, State of Missouri, have invented a new, original, and ornamental Design for Shoes, of which the following is a specification, reference being had to the accompanying drawing, forming part thereof.

The figure is a perspective of the shoe embodying my design, the dots being intended to indicate small perforations of the leather or other material forming the shoe upper.

I claim:

The ornamental design for a shoe, substantially as shown and described.

CHESTER F. REITH.
